UNITED STATES PATENT OFFICE.

ISRAEL E. HELLER, OF BUFFALO, NEW YORK.

MEANS AND METHOD OF MANUFACTURING INTERFOLDED PIECES OF CLOTH, ETC.

Application filed October 14, 1921. Serial No. 507,777.

To all whom it may concern:

Be it known that I, ISRAEL E. HELLER, a citizen of the United States, residing at Buffalo, in the county of Erie and State of New York, have invented certain new and useful Improvements in Means and Methods of Manufacturing Interfolded Pieces of Cloth, etc., of which the following is a specification.

10 My invention relates to improvements in methods of manufacturing and inter-folding strips or pieces of cloth, paper or other material so that stacks or bundles of interfolded pieces may be placed in a container and one piece after another be withdrawn therefrom.

While my invention may be utilized in manufacturing similarly-shaped pieces of paper and inter-folding them, it is especially designed for manufacturing and inter-folding similarly-shaped pieces of cloth adapted for use in clothing factories, shirt factories, and other similar establishments in which the making of garments requires 25 small similarly-shaped pieces of cloth. For example, in clothing factories, pockets, pocket facings, and other parts of a coat, trousers, or other garment are sewed in place by an operative, and I have in mind 30 to arrange pieces for this purpose in a systematic manner so that one after another can be taken up for use without waste of time or loss of pieces.

One of the objects of my invention is 35 the provision of improved and simplified means for cutting similarly-shaped pieces from a roll or bolt of material and inter-folding the same during the course of cutting such pieces.

40 Another object of my invention is the provision of an improved and simplified method for cutting similarly-shaped pieces from a roll or bolt of material and inter-folding the same during the course of cutting such pieces.

45 A further object of my invention is the provision of a method in which two lengths of cloth or other material are slitted transversely, or substantially so, thence folded 50 and cut lengthwise to divide the folded cloth into narrow parts, whereby small pieces are formed and arranged in stacks or bundles having alternate pieces lying in contact with intermediate pieces, said intermediate pieces receiving opposite ends of the 55 alternate pieces between their folded por-

tions so that one piece after another may be removed from each stack or bundle without disarranging the relation of the next piece to the succeeding piece or pieces in the stack 60 or bundle.

My invention consists in the means and novel method of slitting, folding and cutting pieces of cloth, paper or other material, whereby and wherein the cutting of the material will convert the folded material into 65 stacks or bundles of inter-folded pieces of material.

The invention further consists in the novel means and in the arrangement of parts employed to manufacture inter-folded pieces of material, and also in the novel method of manufacturing the same, as will be herein-after described and more particularly pointed out in the subjoined claims. 75

In the drawings:—

Fig. 1 is a longitudinal section through a part of a machine showing the elements thereof embodying my invention in some- 80 what diagrammatic form.

Fig. 2 is a sectional plan view of the same, the section being taken through the slitting device.

Fig. 3 is a plan view of overlying pieces of cloth or other material slit transversely 85 or approximately so, in accordance with my invention.

Fig. 4 is a perspective view of a portion of the cloth or other material folded after being slit transversely. 90

Fig. 5 is a perspective view of a portion of a stack or bundle of small pieces of cloth showing the result of my improved means and methods for manufacturing such a product. 95

Fig. 6 is a perspective view of a portion of the slitting device.

Fig. 7 is a horizontal section taken on line 7—7, Fig. 6.

Fig. 8 is a detached perspective view of 100 one of the pieces of cloth separated from the bundle of which it formed part.

In the machine part of my invention I have illustrated two bolts of cloth designated by the numeral 10, which are mounted 105 one above the other in any suitable manner to permit the slab 11 thereof around which the cloth is wound to be rotated. The manner of rotating and supporting said bolts of cloth forms no parts of my invention, 110 and when cutting paper or other material and inter-folding the same in accordance

with my invention, the paper or other material may be arranged in roll form preparatory to passing the same through the machine.

5 For clearness, I have illustrated the cloth as it leaves the bolt 10 by heavy lines, as at 12. The two lengths of cloth are brought together, one above the other, by passing them between rollers 13. After passing between said rollers the two lengths of cloth are delivered or drawn onto a table 14 supported in any suitable manner, the lower length of cloth passing forwardly in contact with the table while the upper length travels in contact with the lower length for a short distance and is thence directed upwardly and forwardly at an angle to the lower length, as at 15, the change in direction of travel being provided for by a guide roller 16 positioned over the table a short distance in advance of the pair of rollers 13. In a plane forward of the guide roller 16 is a second guide roller 17, elevated from the table 14, and over this guide roller the upper 25 layer of cloth is adapted to pass, it being thence directed downwardly and forwardly to and underneath a guide roller 18. Both layers of cloth extend forwardly above the table, and a short distance in advance of the guide roller 18, a retainer roller 19 is arranged.

20 designates a reciprocating folder member extending upwardly through the table directly in advance of the retainer roller 19, and 21 is a second reciprocating folder member arranged above the table 14 and adapted to co-act with the folder member 20, which latter extends upwardly through an opening 22 formed in the table. The folder member 40 20 is spaced from the retainer roller 19 approximately a distance equaling the thickness of the two lengths or layers of cloth while the folder member 21 is spaced from the folder member 20 a similar distance. 45 The folder member 20 moves upwardly through the opening 22 in the table and carries the two lengths or layers of cloth upwardly beyond the plane of the retainer roller 19, while the folder member 21 moves 50 downwardly and carries the two layers of cloth downwardly along the front of the folder member 20.

As the two folder members move away from the layers of cloth, suitable means not 55 embodied in this invention, but commonly used, may be provided for advancing the folded portion of the cloth and pressing the folds together in the manner shown in Fig. 4.

60 Situated between the rollers 13 and the guide roller 16 is a slitting device 23, which may be raised and lowered in any suitable manner, said slitting device comprising a head 24 in the form of a solid bar and a series of obliquely-disposed cutting blades 65 25 entered in depressions 26 formed in said

head, each of said cutting or slitting blades having a cutting or slitting edge 27 at its lower end. Directly beneath the slitting device, the table may be provided with a transverse groove or depression 28 in which a 70 wooden or other filler member 29 may be placed so that the cutting edges of the cutting or slitting blades 25, when lowered, will pass through the two layers of cloth and come in contact with the wooden or other member 29 inserted in the table to prevent dulling of the blades.

As clearly shown in Figs. 1 and 2, the cutting blades slit the two layers of cloth simultaneously, the slits being arranged in a 80 transverse series, each slit being formed obliquely through the cloth and adjoining slits being preferably slightly overlapped, as clearly shown at 32 in Figs. 2 and 3.

The upper layer of cloth, by reason of its 85 being passed over the elevated guide roller 17, has at all times a stretch between the two guide rollers 16 and 18 which is longer than the stretch of the lower layer between said last-mentioned guide rollers, and the two 90 layers of cloth are again brought together at the guide roller 18, after being separated by the guide roller 17. The elevated guide roller is so positioned that the additional length of the stretch of the upper layer 95 extending from the guide roller 16 to the guide roller 18 equals one-half the distance between the slits formed in the layers; consequently, the transverse series of slits in the upper layer of cloth become positioned midway between the transverse series of slits in the lower layer after the two layers come together at the guide roller 18, as clearly shown in Fig. 3.

The parts are so arranged and timed in 105 operation that the folds made by the reciprocating folder members 20 and 21 will be along the transverse series of slits 30 of both the upper and lower layers, as clearly shown in Fig. 1, and all slits will be at the inside 110 of the folds, as best shown in Figs. 1 and 4. The two layers of cloth are advanced in a regular manner and the slitting device timed in operation to slit them at regular intervals along the lengths thereof; the rotation of 115 the guide rollers 16, 17 and 18 being also timed to assure the proper placing of the transverse slits in the upper layer centrally between the transverse slits of the lower layer.

When the two layers of cloth are slit transversely, or partly severed, as it may be termed, and folded, they will have the appearance shown in Fig. 4, embodying what may be termed a zig-zag fold, with the folds 125 along the transverse slits, both the slits of the inner and outer layer being at the inside of the folds. The cloth thus arranged is then prepared to be cut lengthwise along the lines 31, shown broken in Fig. 3 and dotted 130

first-mentioned guide rollers whereby the stretch of one layer of cloth between said two first-mentioned guide rollers is longer than the corresponding stretch of the other 5 layer.

7. In a machine of the character described, the combination of a table over which overlying layers of cloth are passed, a slitting device having spaced slitting elements thereon adapted to simultaneously slit the two layers of cloth, and means in advance of said slitting device for staggering the slits of said layers of cloth so that the slits of one will be positioned between the 15 slits of the other.

8. A machine of the character described, comprising a table, means for forming oblique slits transversely in said layers of cloth at regular intervals, means for staggering the slits of the upper layer with respect to the slits of the lower layer, and means for folding said layers in zig-zag form along the lines of said slits.

9. A machine of the character described, 25 comprising means for simultaneously slitting two overlying layers of cloth transversely with the slits arranged obliquely in transverse series and overlapped, means for positioning the transverse series of slits in 30 one layer centrally between the transverse slits of the other layer, and means for folding the slitted layers of cloth in zig-zag form with the slits of each layer at the inside of alternate folds.

35 10. The method of manufacturing inter-folded pieces of cloth or other material, which consists in placing two layers of cloth one above the other and causing said cloth to travel; in slitting the same trans- 40 versely at regular intervals; in causing one layer of cloth to move along a longer course than the other between two points to stagger the slits of the two layers; in folding the two layers along the slits; and in cutting 45 the cloth longitudinally to form bundles or stacks of inter-folded pieces.

11. The method of manufacturing inter-folded pieces of cloth or other material, which consists in placing one layer of cloth 50 upon another and moving said layers together in one direction; in slitting both layers of cloth transversely to partly sever the same at regular intervals; in separating the two layers after being slit to cause one 55 layer to travel over a longer stretch than the other; in bringing the two layers of cloth together with the slits in each staggered; in folding the cloth along the trans-

versely slitted portions; and in severing the cloth lengthwise to provide stacks or bundles 60 of small inter-folded pieces.

12. The method of manufacturing inter-folded pieces of cloth or other material arranged in stacks or bundles, which consists in placing one layer of cloth upon another; 65 in partly severing both layers of cloth along transverse lines at regular intervals; in staggering the partly severed portions of cloth of one layer with respect to the other, in folding the cloth in zig-zag form along 70 the partly severed lines, and in cutting the cloth lengthwise to form bundles of small inter-folded pieces of cloth or other material.

13. The method of manufacturing pieces 75 of cloth or other material arranged in stacks or bundles, which consists in placing one layer of cloth upon another; in transversely slitting the two layers of cloth simultaneously with unsevered portions at adjacent ends of adjoining slits, in causing one layer of cloth to move along a greater stretch than the other to bring the slits of one between the slits of the other, in folding the cloth to bring the slits of each layer at 80 the inside of folds, and to sever the cloth lengthwise at adjacent ends of adjoining transverse slits to form stacks or bundles 85 of small inter-folded pieces.

14. The method of manufacturing inter-folded pieces of cloth or other material, 90 which consists in placing one layer of cloth upon another and moving the same; in slitting both layers of cloth transversely to form transverse series of oblique slits at regular intervals along the layers with adjacent ends of adjoining slits overlapped; in then positioning the slits in one layer midway between the transverse slits of the other layer; in folding the two layers in zig-zag 95 form to bring the slits of both layers at the inside of the folds; and in finally severing the folded layers longitudinally along lines passing between the overlapping ends of adjoining slits to form bundles of small 100 inter-folded pieces.

15. In a machine for folding overlying strips of material, the combination of a support over which said material is passed, means for partly severing the material transversely at intervals, and means for 110 causing one of the layers to travel along a greater distance than the other between two points.

In testimony whereof I affix my signature.
ISRAEL E. HELLER.

in Fig. 4, said lines passing through the overlapping portions of adjoining slits in each transverse series and through the spaces 32 between said overlapping portions. Consequently, when the cloth is cut lengthwise, a number of stacks or bundles 33 are formed, such as shown in part in Fig. 5. When thus cut into lengths, the folded condition previously existing becomes an inter-folded condition in which one-half of each piece of cloth is folded between the two halves of the adjoining pieces of cloth. In this manner a large number of bundles or stacks of inter-folded small pieces of cloth are provided, which are adapted to be used within a container and withdrawn therefrom, one after another in the manner of inter-folded paper towels arranged within containers. This will enable operators within clothing factories and similar establishments to have the small pieces of cloth handy and permit the operator to withdraw one after another, as needed, without opportunity of wasting any or losing time in selecting a piece. It is of course understood that, bolts of cloth or rolls of other material can be cut to various widths and lengths and that stacks or bundles of pieces of the kind mentioned may be formed in different sizes and kept conveniently at hand within containers to be withdrawn, one at a time.

It will be clear from the foregoing description that the portions of the layers of cloth between successive oblique slits in the length thereof and between the longitudinal edges and adjacent broken or dotted lines 31, or between adjacent broken or dotted lines 31, will be formed into individual pieces, and as the slits of the lower layer of cloth are arranged centrally between the slits of the upper layer of cloth, each piece of cloth overlaps one-half of two other pieces and is folded centrally between its ends, with the result that the pieces are inter-folded as shown in Fig. 5.

The overlapping of the oblique slits of each transverse series assures a complete severance or division of the two layers of cloth, both along the end and longitudinal edges of the small pieces of cloth manufactured in inter-folded condition, and each piece will or may have a small incision near opposite ends, as at 34, extending from the longitudinal edges thereof inwardly, as shown in Fig. 8, but this incision will in no manner interfere with the proper use of the piece, and while said incisions have no real advantages in themselves, they are the result of the method of manufacturing the pieces and enable such pieces to be manufactured in an inter-folded condition and in bundles or stacks ready to be placed in containers or be otherwise used.

I desire it to be understood that I do not wish to lay any claim to the particular man-

ner shown of folding the two layers of cloth, as this may be accomplished in various ways, but it is essential to my invention that the folds, regardless of how they are made, be made along the transverse series of oblique slits, the material being preferably folded in one direction along alternate series and in the other direction along the intermediate series of slits so that all slits will be at the inside of the folds, as best shown in Fig. 1. 75

Having thus described my invention, what I claim is:—

1. In a machine for folding overlying strips of cloth, the combination of a support over which said cloth is passed, means for partly severing the cloth transversely at intervals, and means for causing one of the layers to travel along a greater distance than the other between two points. 80

2. A machine of the character described, comprising a support over which two overlying strips of cloth are passed, means for partially severing the overlying layers transversely, and means for causing one of the layers to travel along a greater distance 90 than the other between two points to arrange the lines of partial severance of one layer between the lines of partial severance of the other layers.

3. A machine of the character described, comprising a support over which overlying layers of cloth are passed, means for transversely slitting said layers, and means for changing the relative relation of said layers to bring the slits of one layer between the 100 slits of the other layer while passing over said support.

4. A machine of the character described, comprising a support over which two overlying layers of cloth are passed, means for 105 transversely slitting said layers, means for separating the layers after being slit transversely and for bringing said two layers together at a distant point.

5. A machine of the character described, comprising a table over which two overlying layers of cloth are passed, means for transversely slitting said layers at regular intervals, two spaced guide members retaining the upper layer of cloth against the 115 lower layer, and an elevated guide member in a plane between said two spaced guide members, said guide members being arranged to space the slits in the upper layer centrally between the slits in the lower layer 120 after having passed said guide members.

6. A machine of the character described, comprising a flat table over which two overlying layers of cloth are pressed, a slitting device for transversely slitting both layers 125 of cloth simultaneously, a guide roller in advance of said slitting device, a second guide roller spaced from said first-mentioned guide roller, and a third guide roller in a different horizontal plane than said two 130
